(57) **CLAIM**

The ornamental design for a ceiling fan blade, as shown and described.

DESCRIPTION

FIG. 1 is a front elevation view of a ceiling fan blade according to the present design;

FIG. 2 is a right side elevation view of the ceiling fan blade shown in FIG. 1;

FIG. 3 is a top plan view of the ceiling fan blade shown in FIG. 1;

FIG. 4 is a bottom plan view of the ceiling fan blade shown in FIG. 1;

FIG. 5 is a left side elevation view of the ceiling fan blade shown in FIG. 1;

FIG. 6 is a top perspective view of the ceiling fan blade shown in FIG. 1; and,

FIG. 7 is a bottom perspective view of the ceiling fan blade shown in FIG. 1.

The broken lines in the Figures are included for the purpose of illustrating environment and form no part of the claimed design.
